US00D891999S

(12) **United States Design Patent** (10) **Patent No.:** **US D891,999 S**
Carlini (45) **Date of Patent:** **** Aug. 4, 2020**

(54) **TIE ROD CONNECTOR**

(71) Applicant: **Aircraft Gear Corporation**, Loves Park, IL (US)

(72) Inventor: **Sean M. Carlini**, Rockford, IL (US)

(73) Assignee: **Aircraft Gear Corporation**, Loves Park, IL (US)

(**) Term: **15 Years**

(21) Appl. No.: **29/689,319**

(22) Filed: **Apr. 29, 2019**

CLAIM

The ornamental design for a tie rod connector, as shown and described.

DESCRIPTION

FIG. 1 is a left, front, and top perspective view of a tie rod connector showing my new design, where portions thereof are shown with cross hatching to indicate orange colored surfaces;

FIG. 2 is a front elevational view of the tie rod connector of FIG. 1;

FIG. 3 is a top plan view of the tie rod connector of FIG. 1; FIG. 4 is a cross sectional view of the tie rod connector of FIG. 1 taken through line 4-4 of FIG. 2;

FIG. 5 is a right end view of the tie rod connector of FIG. 1, the broken lines and circular interior region forming no part of the claimed design;

FIG. 6 is a left end view of the tie rod connector of FIG. 1; and,

FIG. 7 is a left, front, and top perspective view of the tie rod connector of FIG. 1 with one environment being shown in dotted lines, the environment not forming any part of the claimed invention.

1 Claim, 4 Drawing Sheets
